UNITED STATES PATENT OFFICE

152,019

DESIGN FOR A BOOK END

David Rego, Fall River, Mass.

Application April 9, 1947, Serial No. 138,261

Term of patent 7 years

(Cl. D33—1)

To all whom it may concern:

Be it known that I, David Rego, a citizen of the United States, residing at Fall River, in the county of Bristol and State of Massachusetts, have invented a new, original, and ornamental Design for a Book End, of which the following is a specification, reference being had to the accompanying drawing, forming part thereof.

I claim:

The ornamental design for a book end, as shown.

DAVID REGO.
